(57) **CLAIM**

The ornamental design for the digital multifunction printer,
as shown and described.

DESCRIPTION

FIG. 1 is a perspective view of a digital multifunction printer showing our new design;

FIG. 2 is a front view of the digital multifunction printer;
FIG. 3 is a rear view of the digital multifunction printer;
FIG. 4 is a right view of the digital multifunction printer;
FIG. 5 is a left view of the digital multifunction printer;
FIG. 6 is a plan view of the digital multifunction printer;
FIG. 7 is a bottom view of the digital multifunction printer;
FIG. 8 is an enlarged perspective view of the portion
between A and B of FIG. 6 of the digital multifunction
printer;

FIG. 9 is an enlarged cross-sectional view taken along lines
D-D in FIG. 6 of the digital multifunction printer; and,
FIG. 10 is an enlarged cross-sectional view taken along lines
C-C in FIG. 6 of the digital multifunction printer.

The broken lines shown in the drawings represent portions
of the printer that form no part of the claimed design.

The item is a multifunctional machine that combines the
functions of a copier, scanner, and printer. The part for which
a design registration is claimed is mainly used to temporarily
place a paper clip.
